GOVERNOR FOR POWER ENGINES

Ove Petersen, Gentofte, near Copenhagen,
DenmarkApplication January 9, 1940, Serial No. 313,112
In Denmark January 30, 1939

1 Claim. (Cl. 264—1)

This invention relates to internal combustion engines, which with a view to their employment as propelling machinery in vessels, are provided with an emergency governor serving to prevent a dangerous increase of the speed of revolution when the load disappears wholly or partly due to the propeller being raised more or less out of the water as a result of pitching of the vessel.

Known governors of this kind comprise an oscillating lever actuated in time with the revolution of the engine and carrying a pendulum body, which is normally urged by a spring into an inoperative position. When the speed of the engine increases materially above the maximum permissible speed, the pendulum body, owing to the inertia forces when the oscillating lever changes its direction of movement at one end of its stroke, moves out of its inoperative position and thereby engages a normally stationary system, the passive system, which is thereby moved with the lever when the latter is moving in one direction. By this means a decrease in or interruption of the fuel supply to some or all of the cylinders of the engine is effected.

Normally the passive system is immediately restored into its normal position in which it leaves the fuel pumps undisturbed to deliver the quantity of fuel to which they have been adjusted by means of the ordinary charge controlling lever, so that the engine, after a short interruption or decrease of the fuel supply by which the speed is reduced, again operates normally. The restoring of the passive system may be effected by means of an abutment on the oscillating lever. Such an abutment may be rigidly mounted on the lever, but advantageously the abutment is arranged on another spring-urged pendulum body so that it normally projects for engagement with the passive system when the latter has been removed from its initial inactive position, but is retracted owing to inertia forces when the speed of the engine exceeds a given speed. In the latter case the passive system will be left in the position corresponding to a decreased fuel supply while the oscillating lever completes one or more oscillations, and the passive system will not be restored into its initial position until the speed of the engine is reduced below that at which the inertia forces on the latter pendulum body are overcome by the spring force acting thereon. By this arrangement an additional security against an unpermissible increase in the speed of engine owing to pitching of extraordinary long duration is obtained.

Governors of this kind are described, for ex-

ample, in the British specification No. 333,085 and the United States Patent No. 2,116,025.

It is known in such governors to provide means for adjusting the tension of one or more springs acting upon the pendulum bodies, such means comprising either an adjustment screw mounted upon and reciprocating with a spring housing on the oscillating lever, or a hand wheel mounted on some suitable stationary engine part and connected to a spring housing on the oscillating lever by means of a flexible shaft. These means are disadvantageous because they do not allow the spring tension to be adjusted with such accuracy that the governor becomes operative immediately the engine speed exceeds a given value, and because the operation of these means depends either upon the engineer's skill in timing the movements of his hand in relation to the oscillating lever or upon the functioning of a light flexible shaft. Such a shaft is, however, liable to become damaged especially when one end has to move rapidly up and down.

According to the present invention, these disadvantages are obviated in that the means for transmitting the adjusting movement for regulating the spring tension comprises an adjustment shaft journaled on the oscillating lever and means, for example a cylindrical rack, mounted co-axially with the pivot of the oscillating lever whereby the adjustment shaft can be operated. The cylindrical rack or the like can then be operated by a stationary hand wheel, so that the adjustment of the spring tension can be carried out by means of the stationary hand wheel or like member and transmitted to the spring housing by reliable means. Consequently it becomes possible under all circumstances to adjust the governor so as to become operative immediately the engine speed exceeds the maximum permissible limit under the prevailing conditions and the engine can, therefore, be run without danger at a speed which lies very slightly below the said limit. It therefore becomes possible to set the passive system in such a manner that, when operated, it adjusts the fuel pumps to deliver a quantity of fuel corresponding to idle running at normal speed, so that even pitching of long duration with the propeller out of the water cannot cause the engine to run unduly fast, while on the other hand no material reduction in speed, and consequently of the power output, when the propeller is again submerged, takes place.

The passive system may be restored either by means of a fixed abutment on the oscillating

lever or by means of a second pendulum body which is normally held in an operative position by means of a spring but is retracted when the speed of the engine exceeds a given speed, and in the latter case similar means may be provided for adjusting the tension of the spring.

In order that the invention may be clearly understood and readily carried into effect, two forms of a governor constructed in accordance with the invention are illustrated by way of example in the accompanying drawings, in which

Fig. 1 shows diagrammatically a side elevation, partly in section, of the first form,

Fig. 2 is a section on the line II—II in Fig. 1 showing the governor head in its position relatively to the passive system,

Fig. 3 is a side elevation of the second form, and

Fig. 4 is a plan view of part of Fig. 3 partly in section.

In the form shown in Figs. 1 and 2 the governor comprises a double-armed lever 7, 13 pivotally supported on a bracket 5 on the engine frame which is not shown. One arm 13 of the double-armed lever is connected to a suitable eccentric device or the like (not shown) of the engine so that an oscillating movement in a vertical plane and preferably in time with the revolutions of the engine is imparted to the lever.

The outer end of the arm 7 is shaped as a flat rectangular head 8 with two apertures 9 and 10 in each of which a pendulum body, 11 and 12 respectively, is mounted. Each pendulum body is journaled on a pin, 14 and 15 respectively, rigidly mounted in the head 8. The pendulum body 11 comprises a ratchet lever 16 which is projected by means of a spring device 17 into the position shown in Fig. 2 in which the pendulum body abuts against an abutment on the head 8. Correspondingly the pendulum body 12 comprises a ratchet lever 18 and is spring-pressed by a spring device 19 so that the ratchet lever is kept retracted against the head 8 resting against an abutment thereon.

The passive system comprises a double-armed lever 1, 2 which is pivotally mounted on the same pivot as the double-armed lever 7, 13 and of which one arm 1 is connected to a linkage system not shown through which the fuel supply of the fuel pumps may be influenced. The second arm 2 is provided with two abutments 3 and 4 which the ratchet levers 18 and 16 respectively engage when in their projected positions.

Each of the spring devices 17 and 19 comprises a generally tubular spring housing 20 having laterally projecting bearing pins and enclosing a helical spring 21, the tension of which may be roughly adjusted by means of an adjustment screw 22. Each spring presses on the pendulum body through the agency of a rod 23.

The housing of the spring device 17 is journaled in two bosses 24 on the head 8 while the housing of the spring device 19 is pivoted eccentrically in a rotatable shaft 25 by means of pins 26. The shaft 25 is journaled in bosses on the head 8 and carries on the inner end towards the pivot of the lever 7, 13 a depending lever 27 which is connected by a connecting rod 28 to a lever 29 on the end of an adjustment shaft 30. The adjustment shaft 30 is journaled in bearings 31 on the lever arm 7 and carries a gear meshing with a cylindrical rack 33 which is axially displaceable co-axially with the pivot of the lever 7, 13. Another gear 34 meshes with the cylindrical rack 33 and is mounted on a shaft 35 journaled in a fixed bearing 36. The shaft 35 may be rotated by

means of a hand wheel 37 and carries an index wheel 38 indicating the degree of rotation.

The operation of the above described governor is as follows.

Provided that the engine is running at its normal number of revolutions the pendulum bodies will occupy the position shown in Fig. 2 in which the ratchet lever 16 has moved the control lever 2 down into its lowermost position shown in Fig. 10 1 by engagement with the abutment 4. When the speed of the engine increases beyond a certain value the inertia forces acting upon the pendulum body 12 will overcome the pressure of the spring device 19 when the head 8 changes its direction of movement in the lowermost position so that the ratchet lever 18 will be thrown out and engage the abutment 3. This causes the control lever 1, 2 to move upwards together with the head 8 during the following upward movement of the double-armed lever 7, 13 to the position shown in Fig. 1. This movement of the control lever 1, 2 effects through the previously mentioned linkage a reduction of the fuel supply by some or all of the fuel pumps, and provision is advantageously made so that the supply of the fuel pumps is reduced to the amount corresponding to idle running at normal speed.

During the following downward movement of the double-armed lever 7, 13 to its lowermost end position the control lever 1, 2 is also swung downwards as a result of the ratchet lever 16 engaging the abutment 4, so that the fuel pumps are again set to deliver the quantity of fuel to which they are adjusted by means of the ordinary speed control device. The temporary reduction of the fuel supply which was effected during the upward and downward movement of the control lever 1, 2 will generally result in such a reduction in speed that the ratchet lever 18 will now remain in the retracted position shown in Fig. 2 so that the control lever 1, 2 will be left in its normal inoperative position shown in Fig. 1. If the speed has not been sufficiently reduced the ratchet lever 18 will, however, again be thrown out and take the control lever with it so that, if the pitching is of long duration, the control lever will follow the oscillating lever 7, 13 through two or more successive oscillations until, owing to the periodic reduction of the fuel supply, the speed has fallen below that at which the ratchet lever 18 is thrown out.

The ratchet lever 16 serves, as will be clear from the above, to restore the control lever 1, 2 into its normal position, but in order to ensure that, under exceptional conditions, the engine shall not attain too high a speed, the ratchet lever 16 is arranged to be withdrawn when a given speed is exceeded. The control lever 1, 2 will then be left in the position corresponding to reduced fuel supply during at least one downward and upward movement of the oscillating lever 7, 13 that is normally during one engine revolution. When, as a result of this, the speed has been reduced so much that the pressure of the spring device 17 on the pendulum body 11 overcomes the inertia force thereon, the ratchet lever 16 is again thrown out into the position shown in Fig. 2 whereafter it restores the control lever to the normal position of the following downward movement.

According to the invention the spring load on the one pendulum body, namely the pendulum body 12, can be adjusted while the engine is running, and the said adjustment is carried out by rotating the shaft 25 in which the spring hous-

ing is eccentrically suspended. As will be clear from Fig. 2, when the shaft 25 is rotated, the bearing pins 26 of the spring housing will move nearer to or further away from the pendulum body 12 so that the spring tension may be very finely adjusted. The adjusting movement is transmitted from the hand wheel 31 through the above described transmission means which allow of variations of the adjustment to be made even while the engine is running because the cylindrical rack 33 is arranged co-axially with the pivot of the oscillating lever 7, 13.

It is therefore possible as previously mentioned to adjust the speed limit at which the pendulum body 12 is thrown out and reduces the fuel supply very exactly according to the conditions prevailing at any moment, so that it is possible to run the engine at or approximately at normal speed even in very bad weather without danger of exceeding the maximum permissible speed.

The form shown in Figs. 3 and 4 differs from the form described mainly in the construction of the device for adjusting the spring tension. On the shaft 25 in the head 8, by means of which the spring tension is adjusted, is mounted a gear wheel 39 which meshes with another gear wheel 40 on a shaft 42 journalled in a bearing 41. The shaft 42 carries at its other end a gear wheel 43 meshing with a gear wheel 44 on a shaft 45 which is journalled co-axially with the pivot of the oscillating lever 7, 13. The shaft 45 may be

rotated by means of an adjustment head 46 and carries on a screw-threaded portion 47 a nut 48 which is displaceable but not rotatable and has an index mark indicating the spring adjustment on a scale 49.

Although, in the forms described above, the spring tension on only one of the pendulum bodies is capable of adjustment while the engine is running, it is obvious that the spring tension on the other pendulum body might also be similarly adjustable, in which case a very accurate control may be obtained.

The spring devices and their adjustment means illustrated and described are only examples and may obviously be varied.

I claim:

An engine governor having an oscillating lever, a pendulum body pivotally mounted thereon, a spring housing with a spring acting upon the said pendulum body for keeping the same in one end position against the action of inertia forces below a certain limit of engine speed, a rotatable shaft mounted on said oscillating lever with its axis parallel to the pivot axis of the pendulum body, the said spring housing being pivotally mounted on said shaft with its pivot axis parallel to but not co-inciding with that of the said shaft, and an adjusting shaft mounted co-axially with the pivot of the oscillating lever and operatively connected with the said rotatable shaft.

OVE PETERSEN.
